No. 839,284.

PATENTED DEC. 25, 1906.

I. GERACI.
COAT HANGER.
APPLICATION FILED FEB. 4, 1905.

UNITED STATES PATENT OFFICE.

IGNATIUS GERACI, OF WASHINGTON, DISTRICT OF COLUMBIA, ASSIGNOR OF ONE-HALF TO CHARLES LINKINS, OF WASHINGTON, DISTRICT OF COLUMBIA.

COAT-HANGER.

No. 839,284.

Specification of Letters Patent.

Patented Dec. 25, 1906.

Application filed February 4, 1905. Serial No. 244,237.

To all whom it may concern:

Be it known that I, IGNATIUS GERACI, a citizen of the United States, residing at Washington, in the District of Columbia, have invented new and useful Improvements in Coat-Hangers, of which the following is a specification.

My invention has relation to new and useful improvements in coat-hangers, and more especially to that type or character of hangers which support the garment by the shoulders thereof, so that the garment will be suspended in a position as nearly as possible that it assumes when being worn.

15 The primary object of the invention is to construct the hanger of the character mentioned having characteristics of adjustment which will render it adaptable for use with coats tailored to have either square or drooping shoulders.

20 A further object is to provide a coat-hanger which will be simple in construction, satisfactory in use, and having its parts so arranged and connected that they may be readily and conveniently disassembled for purposes of packing or transportation and so as to occupy small space when shipped in large numbers.

25 The invention consists in providing a suspension device which supports oppositely-disposed shoulder-pieces having a pivotal connection at their meeting ends and means for adjusting them on their pivots, each shoulder-piece consisting of a blank of suitable flexible sheet material bent to have the proper conformation to properly support the shoulders of the coat, means being provided to maintain said blanks in their bent or flexed position and against collapsing.

30 I have fully and clearly illustrated my invention in the accompanying drawings, to be taken as a part of this specification, and wherein—

35 Figure 1 is a view in front elevation of a coat-hanger embodying my invention, the shoulder-pieces being shown in one position of adjustment by dotted lines. Fig. 2 is a vertical transverse section through the meeting ends of the shoulder-pieces and centrally 40 through the spacing-block and suspension device, the rigid connecting-bar not being shown. Fig. 3 is a top plan view of my improved hanger. Fig. 4 is a bottom plan view. Fig. 5 is a sectional view taken on the line 5 5

of Fig. 1. Fig. 6 is a plan view of one of the 55 blanks from which the shoulder-pieces are formed.

Referring to the drawings, 1 1 designate the shoulder-pieces, which when the hanger is in use are placed within the coat and which 60 serve as the supporting means for the latter. Each of these shoulder-pieces is made from a sheet or blank 2 of strong flexible sheet material, such as cardboard, strawboard, leather-board, or other similar material.

65 The blank 2 is bounded on its sides by converging lines 3 3. The wider or inner end of said blank, or that end which constitutes the end of the shoulder-piece which is pivoted to the suspension device, is curved, as shown at 70 4, and said curved edge is formed with a recess or cut-away portion 5, which serves a purpose to be made more fully apparent hereinafter. Each blank is provided also at a point on each side of the recess with an aperture 6, said apertures when the blank is bent to form the shoulder-piece alining with each other to provide bearings to receive a pivot for the shoulder-piece, as will be presently set forth. The apertures 6 are preferably 75 bounded by an eyelet 6^a, constituting a bushing to prevent wear of the edges of said apertures incident to movement of the shoulder-pieces on their pivot.

80 To form the shoulder-pieces, each blank is bent or flexed along its longitudinal center to form the curved supporting-surface 7 and the oppositely-disposed depending side portions 8, as clearly shown in the drawings. Means is provided for connecting the side portions 8 to each other, so as to maintain the blank in its flexed position and against collapsing, which means is shown as consisting of a rigid connecting-bar 9, having one end 85 permanently and pivotally attached to the inner side of one of the depending portions 8, as at 10, and having its opposite end bent at an angle thereto to form a hook 11, adapted to detachably engage an eye or other suitable device 12, secured on the inner side of the portion 8 opposite to that to which said connecting-bar is pivoted. The pivoted connection between the connecting-bar 9 and the depending portion 8 is made by fastening to said depending portion a sheet-metal plate 100^a, having an offset portion to provide an eye or loop 10^b, which receives a laterally-bent portion 9^a on the end of the bar 9, the

said bent portion extending through said loop and having its end bent or upset, as at 9^b, to prevent dislodgment of said bar 9. The strap or plate 10^a is secured in position 5 by means of the well-known commercial eyelet-rivets, which provide an extremely inexpensive and at the same time efficient fastening device. The eye or loop for the hooked end of the connecting-bar is shown 10 as having the same form and construction as the strap or plate 10^a, and therefore need not be specifically described.

It will be seen that when the blank is flexed to form the shoulder-piece and the 15 hooked end of the bar 9 engaged within the eye 12 the blank will be effectually held in its flexed position and against collapsing and that the disengagement of the hooked end of said bar will permit the blank to be 20 flattened out so that it may be conveniently packed for transportation. When the blank is flattened out, the connecting-bar 9 may be folded down upon the face of the blank so as to occupy but small space and whereby the 25 blank and its appurtenances are practically flat, as shown in Fig. 6.

The shoulder-pieces constructed as above described are duplicates in every detail, so that no rights or lefts have to be considered 30 when forming the blanks or in assembling said shoulder-pieces to provide the complete hanger. As shown in the drawings it will be seen that the blanks 2 are formed at the wider end with two extensions 13 13, which 35 are formed by the recess 5. The shoulder-pieces, as above described, are arranged with the extensions 13 in interlocked relation, the extension on one side of each shoulder-piece being disposed in engagement with 40 the corresponding extension on the opposite shoulder-piece, each shoulder-piece having one of its extensions arranged in the space between the extensions on the opposite shoulder-piece and one extension arranged 45 outside said space, the said extensions overlapping each other, as clearly shown in Fig. 4 of the drawings. When the shoulder-piece are in the positions just set forth, the apertures 6 therein register and are adapted to receive a pivot upon which the shoulder-pieces 50 swing when their inclination is being adjusted.

14 designates a suspension-hook adapted to engage any suitable supporting device to 55 support the coat-hanger in operative position. The shank of this hook is formed with an offset portion 15 to provide a clearance-space for the collar of the coat when the latter is in position on the shoulder-pieces, and below 60 said offset portion the shank is carried downwardly in a vertical direction, as at 16, and is then doubled upon itself, as at 17, the end of the shank being carried back along the vertical portion 16 to a point intermediate the 65 ends of the latter and is then bent at an angle

to the said vertical portion to provide a pivot-pin 18, all as clearly shown in Figs. 1 and 2. This pivot-pin 18 is run through the alining apertures 6 in the extension 13 of the shoulder-pieces and is of sufficient length to have its free end project for a short distance beyond the face of the said depending portions 8, said end being threaded, at at 19, and engaged by a washer and wing-nut 20. In the space between the interengaging extensions 75 of the shoulder-piece and upon the pivot-pin 18 is a spacing sleeve or block 21, against which and also the doubled portion of the shank of the supporting-hook the pivoted ends of the shoulder-pieces are forced and 80 held by the wing-nut 20 when the latter is secured upon the threaded end of the pivot-pin 18, whereby to give rigidity to the structure.

It will be seen from the above description 85 taken in connection with the drawings, that the shoulder pieces are free to swing upon the pivot to assume various inclinations suitable for supporting a coat having either square or drooping shoulders, and means will 90 now be described for holding the shoulder pieces in the position to which they may be adjusted. The means I preferably employ for accomplishing the object stated consists in providing one of the extensions of each 95 blank 2 with a plurality of socket-fastenings 22, arranged in a curved line and located substantially as shown in Fig. 6 of the drawings, and the opposite extension of the blank is provided with a single head 23.

It might be stated that the extension of each blank which, when the shoulder-pieces are formed and assembled, comes between the extensions on the opposite shoulder-piece, is the one carrying the head, and extension on 105 the outside carries the sockets, the arrangement being such that the sockets on one shoulder-piece will be in position to coöperate with the head on the opposite shoulder-piece, and by swinging the shoulder-pieces on 110 their pivot to the desired inclination and snapping the socket-fastening on one shoulder-piece over the head on the opposite shoulder-pieces, said pieces will be held immovable on their pivots and maintained in adjustable 115 position.

Having thus described my invention, what I claim, and desire to secure by Letters Patent, is—

1. In a coat-hanger, a supporting device, 120 shoulder-pieces movably connected at their inner ends to said device, each shoulder-piece consisting of a blank of flexible sheet material flexed along its longitudinal center, rigid means for maintaining the blank in flexed 125 position and against collapsing, and means for adjusting the shoulder-pieces to various angles of inclination.

2. In a coat-hanger, a supporting device, shoulder-pieces movably connected at their 130

inner ends to said device, each shoulder-piece consisting of a blank of flexible sheet material flexed along its longitudinal center to provide a curved supporting-surface and depending portions, rigid means connecting said depending portions to maintain the blank in flexed position and against collapsing, and means for adjusting the shoulder-pieces so that the supporting-surfaces may assume various angles of inclination.

3. In a coat-hanger, a shoulder-piece formed from a blank of flexible sheet material, flexed to form said shoulder-piece, and rigid means connecting portions of said blank whereby it is maintained in flexed position and prevented from collapsing.

4. In a coat-hanger, a supporting device, similar shoulder-pieces mounted on said device, each consisting of a blank of flexible sheet material flexed along its longitudinal center, and rigid means connecting different portions of each of said blanks for maintaining them in flexed position and against collapsing.

5. In a coat-hanger, a supporting device, shoulder-pieces movably mounted on said device, each shoulder-piece consisting of a blank flexed along its longitudinal center, means for maintaining the blank in flexed position comprising a connecting-bar pivoted to one portion of the blank and means carried by another portion of the blank to be detachably engaged by the opposite end of the bar, and means whereby the shoulder-pieces may be adjusted and held at different angles of inclination.

6. In a coat-hanger, a supporting device, shoulder-pieces movably mounted on said device, each shoulder-piece consisting of a blank flexed along its longitudinal center, means for maintaining the blank in flexed position comprising a connecting-rod pivoted at one end to one portion of the blank and having a hook at its opposite end, and an eye mounted in another portion of the blank and adapted to receive the hook on the connecting-bar, and means whereby the shoulder-pieces may be adjusted and held at different angles of inclination.

7. In a coat-hanger, a supporting device, shoulder-pieces pivoted at their inner ends to said device, each shoulder-piece consisting of a blank flexed along its longitudinal center to provide a curved supporting-surface and depending side portions, the side portions at the inner end of each shoulder-piece overlapping the side portions of the opposite shoulder-piece, and means for adjustably connecting said overlapping ends whereby the shoulder-pieces may be adjusted and held at different angles of inclination.

8. In a coat-hanger, a supporting device, shoulder-pieces pivoted at their inner ends to said device, each shoulder-piece consisting

of a blank flexed along its longitudinal center to provide a curved supporting-surface and depending side portions, the side portions at the inner end of each shoulder-piece overlapping the side portions of the opposite shoulder-piece, means for adjustably connecting said overlapping ends whereby the shoulder-pieces may be adjusted and held at different angles of inclination, and means for maintaining the blanks in flexed position.

9. In a coat-hanger, a supporting device, shoulder-pieces pivotally and detachably mounted on said device, each shoulder-piece consisting of a blank flexed along its longitudinal center to provide a curved supporting-surface and depending side portions, the side portions at the inner end of each shoulder-piece overlapping the side portions of the opposite shoulder-piece, separable adjusting means connecting said overlapping ends whereby the shoulder-pieces may be adjusted to different angles of inclination, and means for maintaining the blank in flexed position.

10. In a coat-hanger, a supporting device provided with a pivot-pin, shoulder-pieces pivoted on said pin, means for clamping the shoulder-pieces in position on said pin, each shoulder-piece consisting of a blank flexed along its longitudinal center to provide a curved supporting-surface and depending side portions, the side portions at the inner end of each shoulder-piece overlapping the side portions of the opposite shoulder-piece, a separable adjusting means connecting said overlapping ends whereby the shoulder-pieces may be adjusted to different angles of inclination, and means for maintaining the blank in flexed position.

11. In a coat-hanger, a supporting device, provided with a pivot-pin having a threaded end, shoulder-pieces pivoted on said pin, a clamping-nut engaging the threaded end of said pin to clamp the shoulder-pieces in place on the supporting device, each of said shoulder-pieces consisting of a blank flexed along its longitudinal center to provide a curved supporting-surface and depending side portions, the side portions at the inner end of each shoulder-piece overlapping the side portions of the opposite shoulder-piece, a spacing-block on the pivot-pin and between said overlapping ends, and a separable adjusting means connecting said overlapping ends whereby the shoulder-pieces may be adjusted to different angles of inclination.

12. In a coat-hanger, two pivotally-mounted shoulder-pieces, each consisting of a blank of sheet material flexed along its longitudinal center, means for maintaining each blank in flexed position, said means comprising connecting-bars, each pivoted at one end to one portion of a blank, and means carried by another portion to be detachably engaged

by the opposite end of the bar, and means whereby the shoulder-pieces may be adjusted and held at different angles of inclination.

13. In a coat-hanger, two pivotally-connected shoulder-pieces, each consisting of a blank of sheet material flexed along its longitudinal center, means for maintaining each blank in flexed position, and means whereby the shoulder-pieces may be adjusted and held at different angles of inclination.

14. In a coat-hanger, two pivotally-connected shoulder-pieces, each consisting of a blank of sheet material flexed along its longi-

tudinal center, means for maintaining each blank in flexed position, means whereby the shoulder-pieces may be adjusted and held at different angles of inclination, and means for suspending the shoulder-pieces.

In testimony whereof I have hereunto set my hand in presence of two subscribing witnesses.

IGNATIUS GERACI.
